JOHN D. SHEPARD AND RICHARD W. ENGLISH, OF BUFFALO, NEW YORK, ASSIGNORS TO JOHN D. SHEPARD.

Letters Patent No. 92,662, dated July 13, 1869.

IMPROVED HINGE.

The Schedule referred to in these Letters Patent and making part of the same.

To all whom it may concern:

Be it known that we, JOHN D. SHEPARD and RICHARD W. ENGLISH, of the city of Buffalo, in the county of Erie, and State of New York, have invented a certain new and useful Improvement in Self-Locking Blind-Hinges; and we do hereby declare that the following is a full and exact description thereof, reference being had to the accompanying drawings, making part of this specification, in which—

Figure 1 is a top plan view of the lower pair of hinges, with the blind closed.

Figure 2 is an edge view of the same, with the blind open.

Figure 3 is a top plan view of the lower leaf, with the pintle of the other leaf shown in section on the line $x-x$ of fig. 2.

Figure 4 is a plan view of the lower leaf, looking from below upward, and represents the position in which the pattern is placed in the mould for casting.

Our invention consists in the special manner or form of constructing the lower pair of hinges for blinds, whereby they are rendered automatically double-locking, when the blind is thrown open.

In constructing our improved hinge, we make two leaves, C and C', each having formed thereon a vertical plate, or flange, a , by which they are secured to the blind and the casing, respectively, in the usual manner, so that the leaves C and C' shall project at right angles from the flange a , and a horizontal plane, as represented in fig. 2.

These leaves C and C' are both made of the same form on their periphery, as represented in figs. 3 and 4, they being eccentric or cam-shaped on their rear edge, and having an offset, or shoulder, g , formed on their outer edge, at a point directly opposite, and in line with the rear edge of the flange a , as shown clearly in fig. 3.

The adjoining faces of the leaves C and C' are both made flat; with the exception that each has on its rear portion a small flat projection, h , each edge of which is inclined, as shown in figs. 2, 3, and 4, these projections being so located, that when the blind is opened they shall pass one over the other, and have their inner inclined edges lock over or against each other, as shown at e , fig. 2, when the blind is thrown entirely open.

The lower leaf C' is made with an elongated opening, or hole, c , as shown in fig. 3, the longer diameter of this opening standing at right angles to the wall, or casing A, as there represented.

The upper leaf C has a pintle, d , projecting from the centre of its lower face vertically, to fit into the

hole c , and near the lower end of this pintle is a projection, f , standing out horizontally, as shown in figs. 2, 3, and 4.

This projection, or lug f is made of such a size as to permit the pintle d , with it on, to be inserted through the hole c , when turned the long way of the hole, and lock under the leaf C' when turned around.

The other hinge of the blind may be of any suitable form, or it may be a duplicate of the one above described; and though we have spoken of this as the bottom hinge, it is obvious that it may be placed at the top, with equal facility and benefit.

With a hinge thus constructed, and applied to the blind in the usual manner, the operation is as follows:

As the blind is swung open, the projections h ride one over the other, and just as the blind reaches the point where it is to stop, the inclines e of the projections h , working on each other, draw the blind B inward toward the wall, or casing A, thereby causing the shoulders g of each leaf to lock against the rear edge of the vertical flange a of the opposite leaf, as shown in fig. 2, the locking thus being double and automatic in operation.

To unlock the blind or hinge, as is necessary to close it, the bottom of the blind B is shoved outward from the wall, the incline e of the upper leaf riding up on the corresponding incline of the lower leaf, the outward movement withdrawing the shoulders g from behind the edges of the flanges a , when the blind is swung around and closed.

By this manner of forming the hinge, we produce a very cheap, effective, strong, and durable hinge, and one that can be cast complete, with the screw-holes in, ready for use.

We are aware that hinges have heretofore been made with elongated openings, and with a shoulder on one leaf for locking the blind open, and, therefore, we do not claim them, broadly; but, having thus described our invention,

What we claim, is—

A hinge, having its leaves provided with the two projections, or inclines h , and the two shoulders g , arranged to lock against the rear edges of the flanges a , substantially as described, whereby the hinge is rendered automatically double-locking, as set forth.

In witness whereof, we have hereunto signed our names, in the presence of two subscribing witnesses.

JOHN D. SHEPARD.

RICHARD W. ENGLISH.
